(57) **CLAIM**

The ornamental design for an integrated lighting module, as shown and described.

DESCRIPTION

FIG. 1 illustrates a top front left perspective view of a new and ornamental integrated lighting module according to a first embodiment;

FIG. 2 illustrates a front view thereof;

FIG. 3 illustrates a back (rear) view thereof;

FIG. 4 illustrates a right-side view thereof;

FIG. 5 illustrates a left-side view thereof;

FIG. 6 illustrates a top view thereof;

FIG. 7 illustrates a bottom view thereof; and,

FIG. 8 illustrates a bottom perspective view thereof.

Broken lines in any of included figures are for illustrative purposes only and form no part of the claimed design.
